UNITED STATES PATENT OFFICE.

EMIL JORGENSEN, OF DES MOINES, IOWA.

FASTENER FOR WINDOW SCREENS.

Application filed May 9, 1921. Serial No. 468,026.

To all whom it may concern:

Be it known that I, EMIL JORGENSEN, a citizen of the United States, and resident of Des Moines, in the county of Polk and State 5 of Iowa, have invented a certain new and useful Fastener for Window Screens, of which the following is a specification.

The object of my invention is to provide a simple, durable and inexpensive fastening device which may be used to secure 10 window screens in position in window openings.

More particularly it is the object of my invention to provide a window screen fastener adapted to be used in connection with 15 windows above the first floor, such as those in apartment houses, the fastener being so arranged that the screen may be easily and quickly placed in position from the interior 20 of the building, and also so constructed that the fasteners may be applied to the window frames from the interior of the building.

A further object is to provide a screen fastener which may be formed of a stamped 25 sheet metal and of two pieces similar except being rights and lefts.

A still further object is to provide a window fastener for screens so arranged 30 that the screen may be easily and quickly placed in position from the interior of the building, and when placed in position, the said fasteners may be locked so that the screen may not be removed from the exterior.

These and other objects will be apparent 35 to those skilled in the art.

My invention consists in the construction, arrangement and combination of the various parts of the device, whereby the objects contemplated are attained, as hereinafter more 40 fully set forth, pointed out in my claims, and illustrated in the accompanying drawings, in which:

Figure 1 is a side elevation of a window 45 and window opening from the interior of a building showing the manner in which my improved fastener is applied to a screen, and the manner in which the said screen is secured in the window opening.

Figure 2 is a detail sectional view taken 50 on the line 2—2 of Figure 1 with the screen slightly elevated to show the relative position of the locking devices to each other as the screen is applied to the window opening.

Figure 3 is an enlarged detail sectional 55 view taken on the line 3—3 of Figure 2.

Figure 4 is an enlarged detail view showing a portion of the window casing in segment, and a modified form of my improved fastening device. 60

Figure 5 is a perspective view of one of the fastener members.

The numeral 10 indicates a wall of a building in which is provided a window opening, the window opening having a 65 frame 11 which is of the ordinary construction. This frame 11 is provided with casings 12, blind stops 13 and a pulley stile 14.

The numeral 15 indicates a screen frame 70 which is of the ordinary construction and is preferably made of a size to cover the opening of the lower window sash, or what is known as a half screen. These screens are usually placed in position resting adjacent to the inner edges of the outside casings 12 75 and adjacent to the outer face of the blind stops 13. This permits the upper window to be raised and lowered inside the screen if so desired. The lower window sash always sets inside of the upper window sash, and 80 for that reason the said lower sash, indicated by the numeral 16, is always free to be moved to an opened or closed position.

After the screen has been placed in position, it has heretofore been rather a difficult 85 problem to fasten the screen in position from the interior without having to obtain a ladder and secure it in position from the outside. This is almost impossible in five or six story apartment houses. The width of 90 the blind stops 13 is usually about three-fourths of an inch. This is the only clearance between the screen and the upper sash, and for that reason it has been somewhat difficult to obtain a fastener that would secure 95 the screen in position from the interior, and at the same time permit the upper window sash to move up and down past the said fastener.

To overcome this difficulty, I have provided a fastening device comprising a sheet metal member 17, provided with openings 18 for screws, one edge of the member 17 being provided with a laterally extending hook member 19, and said member having a slot 100 20 of a width slightly greater than the width of the sheet metal and of a depth substantially equal to one-half of the length of the member 19. I have provided these fastener members in rights and lefts. The width 110 of the member 17 is slightly less than the width of the blind stops 13. On the inner

edge of each of the blind stops 13, I mount two of the members 17 by means of screws 21. One of the members 17 is mounted near the lower end of the blind stops 13 with 5 the hook member 19 extending inwardly and adjacent to the window screen but spaced apart therefrom a distance slightly greater than the thickness of the member 17, as clearly shown in Figure 2. The other member 10 17 is mounted near the upper end of the screen as illustrated in Figure 1. The opposite blind stop is provided with a similar set, with the exception that they are right hand instead of left hand members.

15 A similar set is provided on each of the screen members that rest adjacent to the blind stops, but in an inverted manner, as shown in Figure 2, and held in position by suitable screws 22, and when the screen is 20 in its normal position, the slot 20 of the inverted member will enter the slot 20 of the upright member in such a manner that the screen will be rigidly held against outward movement. When these members 17 have 25 been secured to the screen members 15, the screen is then held in position until it is desired to remove the same which may be easily and quickly accomplished by merely lifting the screen upwardly, causing all of 30 the inverted members 17 to simultaneously disengage the upright members. The screen may then be moved outwardly a slight distance and then pulled in through the window opening if so desired.

35 It will be seen that the screen may be placed in position by a reverse operation, that is, by placing the members 15 against the outer face of the blind stops 13 in a slightly elevated position, then permitting 40 the screen to move downwardly and the inverted hooks will automatically engage the upright hooks.

It sometimes happens that with the windows on the lower floors that it is desirable 45 to lock the screen from being moved from the exterior. This I accomplish by providing a hook 23 which is arranged to be

mounted on the lower one of the screws 21, as illustrated in Figure 4. The hook member 50 is so arranged that when the two fasteners are in a locking position, the hook portion 24 of said hook member will engage the upper edge of the inverted member 19. One of these hooks 23 may be provided on the bottom members of each side of the window 55 opening, and if so desired the hook members may be placed on all of the fastening devices.

By this construction, it will be seen that I have provided a window fastener which is 60 very simple and may be easily and quickly made by the regular die and stamping method, and so constructed that it will occupy a very small amount of space so it may be adapted to the blind stops of the 65 ordinary window construction and will not interfere with the opening or closing of the windows either when in use or out of use.

I claim as my invention:

1. A window fastener member comprising 70 a plate having two opposite edges, screw openings near one of said edges, a laterally extending flange near the opposite edge, said flange being provided with a slot adjacent to said plate and of a width slightly greater 75 than the thickness of the plate, a screw for each of said openings, and a hook member pivotally mounted on one of said screws.

2. The combination of a window frame, a 80 detachable screen frame adjacent thereto, said screen being provided with members having downwardly extending hooks, screws for securing said members to said screen, said window frame being provided with members having upwardly extending hooks 85 to coact with the hooks of said screen, screws for securing the hooks of said window frame thereto, a locking hook member pivotally mounted on one of the screws of each of the last said upwardly extending hook members, 90 substantially as described and for the purposes stated.

Des Moines, Iowa, April 22, 1921.

EMIL JORGENSEN.
